CHUCK

Raymond R. Searles, New Britain, Conn., assignor to The Fafnir Bearing Company, New Britain, Conn., a corporation of Connecticut

Application January 7, 1931. Serial No. 507,184

5 Claims. (Cl. 279—46)

My invention relates to a gripping device, such as a chuck or vise, and more particularly to means for flexing a diaphragm gripping device of the general type set forth in Scaife Patent No. 1,389,272, dated August 30, 1921.

It is an object of the invention to provide a gripping device of the character indicated, which is compact and simple in construction and which is quick in its action.

10 It is another object to provide a gripping device of the character indicated having improved operating means for quickly actuating the diaphragm, and comprising few and simple parts.

15 Other objects and features of the invention will be hereinafter pointed out or will become apparent.

In the drawing which show, for illustrative purposes only, preferred forms of the invention—

20 Fig. 1 is a side view in partial central section illustrating a gripping device embodied in a vise;

25 Fig. 2 is a central sectional view of a gripping device similar to that shown in Fig. 1 but illustrating a different manual operator.

In said drawing, 5 indicates a body, which may be part of a chuck body designed for attachment to a spindle and therefore rotatable, or it may be fixed, as on a turret or bench, so as not to be 30 rotatable relatively to its support. A diaphragm 6 is secured to the body 5, as by means of screws, such as 7. Gripping jaws 8—8 are formed integral with or are secured to the diaphragm, as by means of screws, such as 9, and dowels, 35 such as 10. The gripping jaws herein illustrated are for external gripping of the work piece, such as a bearing ring 11. Clearly, the jaws could be arranged for internal gripping.

With the parts arranged as illustrated, when 40 the diaphragm 6 is flexed outwardly or to the right, the external gripping jaws 8—8 are separated so as to release the work piece 11, and when the diaphragm moves to the left, the gripping jaws 8—8 serve to grip the work piece. Any 45 suitable stop means, such as stop pins 12, may be provided for locating the work piece 11 relatively to the gripping device in general, whether it be a chuck or a vise.

My invention relates particularly to means for 50 flexing the diaphragm. In the form shown I provide an operating rod 13, which is suitably journaled in the body 5, and which rod 13 may be manually operated by a handle 14, as illustrated in Fig. 1, or by a removable wrench 15, 55 as illustrated in Fig. 2. The handle 14 may be

permanently secured to the rod 13, and when a removable wrench 15 is to be employed the upper end of the rod 15 is provided with a suitable socket, as will be understood. The rotatable operating rod 13 actuates means for flexing 60 the diaphragm.

In the form illustrated I employ a cam member, more specifically an eccentric 16, pinned or otherwise secured to the rod 13. With the cam member positioned as illustrated in the drawing, 65 the diaphragm is in such position that the spring of the metal has caused the gripping jaws 8—8 to grip the work piece 11. When the cam member, such as the eccentric 16, is rotated it engages the diaphragm 6 and springs the latter 70 outwardly or to the right as viewed in the drawing. This flexure of the diaphragm causes the gripping jaws 8—8 to separate and permits the removal of the work piece 11 and the insertion of a new work piece. It will be clear that, with 75 a suitably formed cam such as the eccentric, the rod 13 may be turned to such position that the eccentric will be on dead center and will hold the diaphragm in outwardly flexed position, so as to maintain the jaws open, even 80 though the handle 14 or wrench 15 be released.

In the specific form shown the gripping is effected by the spring back of the diaphragm. It will be clear without illustration that if it is desired to positively move the diaphragm in the 85 gripping direction, the cam or eccentric could be engageable with a yoke fixedly attached to the diaphragm, so that movement of the cam or eccentric 16 would positively draw the diaphragm rearwardly in the gripping direction. 90

By the use of an eccentric cam there is a self-contained predetermined limit to the throw thereof, and accordingly the danger of overflexing and distorting the diaphragm or giving a set thereto is prevented, this advantage being in 95 addition to those already set forth.

While the invention has been described in considerable detail and specific forms shown, it is to be understood that various cam formations and various arrangements of different cams and various embodiments of the invention may be made, all within the scope of the invention as defined in the appended claims.

I claim:

1. In a device of the character indicated, a body, a diaphragm secured thereto, gripping jaws carried by the said diaphragm, said body having a chamber immediately adjacent said diaphragm, cam means located in said chamber for flexing 110

105

100

105

said diaphragm, and means for rotating said cam means.

2. In a device of the character indicated, a body, a diaphragm secured thereto, gripping jaws carried by said diaphragm, a rotatable cam member within said body, and means secured to said cam member and extending substantially radially to the outside of said body for rotating said cam member, said cam member being operatively positioned for flexing said diaphragm.

3. In a device of the character indicated, a diaphragm, gripping jaws carried by said diaphragm, a rotatable cam member immediately adjacent one side of said diaphragm and pivotally mounted on an axis substantially parallel to said diaphragm, and means for rotating said cam member for flexing said diaphragm.

4. In a device of the character indicated, a

body, a diaphragm secured thereto, gripping jaws carried by said diaphragm, rotatable means engageable directly with said diaphragm for flexing the latter, said means being rotatable on an axis substantially parallel to said diaphragm, and manually operable means operable from the outside of said body for actuating said rotatable means for flexing said diaphragm.

5. In a device of the character indicated, a body, a diaphragm secured thereto, gripping jaws carried by said diaphragm, a rotatable rod extending substantially parallel to said diaphragm and carried by said body, said rod being operable from the outside of said body, and means carried directly by said rod and rotatable therewith for flexing said diaphragm.
